UNITED STATES PATENT OFFICE

2,055,091

MACHINE FOR USE IN MAKING BOXES

Eugene F. Valley, Rockaway, N. J., assignor to
Stapling Machines Co., a corporation of Delaware

Application March 16, 1935, Serial No. 11,414

5 Claims. (Cl. 140—93)

This invention relates to machines for equipping wired box parts with fastening means and particularly to machines for manipulating a wire secured to a box part to form and perpetuate a bight on the end of the wire.

It is an object of the invention to provide certain improvements in a machine of the type disclosed in U. S. Patent to Rosenmund No. 1,933,031.

It is a further object to provide such a machine with improved means for positioning a box part relative to the wire-manipulating elements to locate the fastening means a predetermined distance from the box part edge.

It is a further object to provide such a machine with box part positioning means adapted to position the box part edge both horizontally and vertically.

It is a further object of the invention to provide such a machine with positioning means adapted 20 to position thin box materials relative to the wire-manipulating elements.

It is a further object of the invention to provide such a machine with presser means to prevent thin box materials from buckling during the positioning operation and to facilitate the correct 25 positioning of such materials.

One illustrative embodiment of the invention is shown in the accompanying drawings, in which:—

30 Figure 1 is a perspective view of two wire-connected box parts upon which the machine of this invention is adapted to operate.

Fig. 2 is a perspective view of one of the box parts after it has been operated upon by the machine of this invention.

Fig. 3 is a plan view of a portion of the table upon which the box parts are positioned and supported during a fastener-supplying operation, certain parts being omitted for clearness of illustration.

Fig. 4 is an enlarged plan view of one of the box part positioning units and includes a box part correctly positioned relative to the wire-manipulating mechanism; certain parts being omitted for clearness of illustration.

Fig. 5 is the same as Fig. 4 but shows the position of the positioning unit after the box part has been correctly positioned and while the box part is being presented to the wire-manipulating mechanism.

Fig. 6 is a side elevation of the cam which moves the box part positioning unit into non-operating position when the supporting table is lowered to present the box parts to the wire-manipulating mechanism.

Fig. 7 is a sectional view taken on the line 7—7 of Fig. 4.

Referring to Fig. 1, the machine of this application is intended to receive on a supporting table the wire-connected box parts designated A and 5 B, sever the connecting wires designated C, form prongs on the severed ends, swing the prongs over onto the box parts to form bights, and drive the prongs into or through the box parts to perpetuate the bights. The completed bights thus formed 10 are shown in Fig. 2 and designated D.

The wire-connected box parts A and B when fed into the machine are positioned on a table or support which is adapted to be lowered to present the connecting wires C to the wire-manipulating 15 elements.

It is desirable that the box parts A and B be correctly located or positioned before the wires C are presented to the wire-manipulating elements. This is accomplished by definitely positioning the 20 front edge of the box part A relative to the wire-manipulating elements. Definitely positioning the box part A also definitely positions box part B because the length of the wires connecting the two box parts are of definite predetermined 25 length.

To definitely position the forward edge of box part A relative to the wire-manipulating elements, stop mechanism is provided which normally lies in the path of travel of the box part and arrests 30 movement of the box part when it strikes the stop mechanism and moves with it to the limit of its travel. After the box part has been definitely positioned against the stop mechanism and the machine started, the stop mechanism is withdrawn from in front of the box part and held in non-stop position during the wire-manipulating 35 operation. The stop mechanism will be described in detail hereinafter.

Associated with the stop mechanism is a presser 40 plate to contact the upper surface of the box part to prevent buckling thereof during its presentation to the stop mechanism. Such presser plate which will also be described in detail hereinafter facilitates the correct positioning of the 45 box part.

When the box parts have been correctly positioned on the supporting table, the machine may be started by throwing into operation a one-cycle clutch. When the machine is started the 50 table is lowered to present the connecting wires C to the wire-manipulating elements which sever the wires, form prongs on the severed ends, swing the prongs over onto the box parts, and drive the prongs into or through the box parts. 55

The wire-manipulating elements and their operation are fully shown and described in the aforementioned patent to Rosenmund No. 1,933,031, reference to which patent is hereby 5 made for a detailed description.

The table upon which the box parts are supported and positioned is shown in skeleton form in Fig. 3. It consists generally of a rectangular frame formed from side bars 1 connected by cross 10 bars 1a. Intermediate cross bars (not shown) may be employed to brace and strengthen the table. Reference to said Rosenmund patent is made for a detailed description of the table.

The improved stop mechanism for positioning 15 the box parts relative to the wire-manipulating elements is best shown in Figs. 3 to 7 inclusive. Referring to Fig. 3, the forward edge of the incoming box part is positioned by contacting with stops 2 located on each side of the incoming box 20 part and normally extending into the path of travel of the box part to be engaged thereby.

The stops 2 are each pivotally and adjustably mounted on an arm 3, the arms 3 being pivotally mounted on plates 4 secured to stock support bars 5, which bars are adjustably secured to cross bar 1a of the table. Stops 2 are normally held in the position shown in Fig. 3 by springs 6 each of which is secured at one end to a stop 2 and at the other end to a portion of an arm 3. 25 Pivotal movement of stops 2 on arms 3 is controlled by pins 7 carried by the stops 2 and which engage the arms 3 at either extremity of the movement of the stops 2.

The upper ends of arms 3 carrying the stops 35 2 are urged toward each other by springs 8, one end of each spring being secured to an arm 3 and the other end to a plate 4. Movement of arms 3 is limited by adjustable stops 9 carried by plates 4 and which engage the lower ends of arms 3.

40 The upper ends of arms 3 carrying the stops 2 are moved away from each other by cam plates 10 (see Fig. 6) which contact with rounded cam surfaces 11 on the arms 3 when the table is lowered to present the box parts and the connecting wires to the wire-manipulating elements. The cam plates 10 are adjustably secured to a fixed part of the machine directly beneath the cam surfaces 11 of the arms 3, so that when the table is lowered 45 the arms 3 will be swung away from each other, i. e., from the position of the arm 3 shown in Fig. 4 to the position of the arm 3 shown in Fig. 5.

Still referring to Fig. 3, when a box part is fed 45 into a machine its forward edge contacts with the stop members 2 and pushes the stop members 2 forward against the action of the springs 6 until the pins 7 contact with the arms 3 and prevent further movement of the stop members 2. 55 When in this position the box part is correctly positioned for a wire-manipulating operation. Both stop members 2 are then in the position of the stop member 2 shown in Fig. 4, i. e., in contact with the forward edge of the box part. 60 When in this position the table is lowered, causing the cam plates 10 to swing the arms 3 away from the box part to the position of the arm 3 shown in Fig. 5.

When the wire-manipulating operation is completed 65 the table rises, thus permitting arms 3 to pivot toward the box part under the influence of springs 8. At this time, however, the stop members 2 (under the influence of springs 6) occupy the pivoted position of the stop member 2 shown 70 in Fig. 5, so that when the stop members swing 75

toward the box part they engage the side of the box part and drag along the side of the box part while it is being drawn through the machine. When the completed box part has been drawn past the stop members 2, the springs 8 move the 5 arms 3 inwardly and the stop members 2 are thus moved into the path of the next oncoming box part in position to engage the front edge of that oncoming box part and position it for the next machine operation.

10 Referring to Fig. 7, each stop member is provided on its forward face with vertically spaced positioning arms 12 and 13 to receive between them the forward edge of the box part and guide it to the body of the stop 2. To facilitate this 15 guiding operation, arm 12 is formed with a beveled surface 14 to provide a wide opening between arms 12 and 13 to receive the forward edge of the box part, which opening gradually becomes 20 narrower as the opening approaches the body of 25 the stop 2. This gradually narrowing opening insures the receiving and correct positioning of the forward edge of the box part regardless of warping or buckling which may be present in thin materials such as are used in the manufacture of wire-bound boxes.

It will be noted that the body of the stop member 2 positions the box part horizontally relative to the wire-manipulating elements and that the arms 12 and 13 position the box part vertically relative to the wire-manipulating mechanism.

To assist in correctly positioning the box part and to prevent undue buckling and to press out warping in the box material, a presser plate 15 is 35 provided at either side of the machine to rest upon and press the box part down against the stock support bars 5. Presser plate 15 is bent upwardly at its forward edge, as shown at 16, to facilitate the entry of the box part under the 40 plate 15. Plate 15 is pressed onto the box part by means of compression springs 17 interposed between the plate 15 and a plate stud 18 which passes through holes in a bracket 19 secured to a stock guide 20 carried by and extending from 45 cross bar 1a of the table.

It will be noted that the presser plates just described in addition to preventing buckling of thin box part material and in addition to pressing out warpage in the box part material, also control the approach of the forward edge of the box part to the stop mechanism and insure the entry of the forward edge of the box part into the openings provided between arms 12 and 13 carried by stop members 2, and insure correct positioning of the box part for a wire-manipulating operation regardless of the tendency of thin box parts to buckle and warp.

Among other advantages this invention provides a dependable means for correctly positioning thin box parts for a wire-manipulating operation and for handling thin box materials wholly unsupported or stiffened by cleats or other box reinforcing members.

It will be understood that the invention is not 65 to be limited to the specific embodiment shown for purposes of illustration as the inventive features of the machine may be used in other forms.

It will also be understood that all of the inventive features need not be used conjointly as 70 they may be used in various combinations as defined in the subjoined claims.

I claim:

1. In a machine of the character described, the combination of wire-manipulating mechanism to 75

- form a bight on a wire secured to a box part and drive the end of the wire into the box part to perpetuate the bight, and means to position the box part relative to the wire-manipulating mechanism, said positioning means including a support for the box part, means yieldingly to press the box part on the support, and a stop member having two vertically spaced arms to receive between them the forward edge of the box part, 5
- 10 the opening between said arms being relatively large to receive the edge of the box part and gradually decreasing toward the body of the stop member to guide the box part to correct vertical position against the body of the stop member.
- 15 2. In a machine of the character described, the combination of wire-manipulating mechanism to form a bight on a wire secured to a box part and drive the end of the wire into the box part to perpetuate the bight, and means to position the 10 box part relative to the wire-manipulating mechanism, said positioning means including a support for the box part, means yieldingly to press the box part on the support, and a stop member having two vertically spaced arms to receive between them the forward edge of the box part, 15
- 20 25 3. In a machine of the character described, the combination of wire-manipulating mechanism to form a bight on a wire secured to a box part and

drive the end of the wire into the box part to perpetuate the bight, and means to position the box part relative to the wire-manipulating mechanism, said positioning means including a movable stop member having spaced arms to receive between them and position the forward edge of the box part, and means to move the stop member into and out of stop position. 5

4. In a machine of the character described, the combination of wire-manipulating mechanism to form a bight on a wire secured to a box part and drive the end of the wire into the box part to perpetuate the bight, and means to position the box part relative to the wire-manipulating mechanism, said positioning means including presser 10 means for the box part and a stop member having two vertically spaced arms to receive between them the forward edge of the box part. 15

5. In a machine of the character described, the combination of wire-manipulating mechanism to form a bight on a wire secured to a box part and drive the end of the wire into the box part to perpetuate the bight, and means to position the box part relative to the wire-manipulating mechanism, said positioning means including a stop 20 25 member having vertically spaced arms to receive between them the forward edge of the box part.

EUGENE F. VALLEY.
